STANCHION FOR A CAR-TOP BOAT RACK

Richard H. Lange, 1339 Rowe Road,
Schenectady, N.Y. 12309

Filed May 29, 1975, Ser. No. 581,976

Term of patent 14 years

Int. Cl. D8—08

U.S. Cl. D8—242

FIG. 2.

FIG. 1.

FIG. 1 is a side view of a stanchion for a car-top boat rack of the present invention.

FIG. 2 is a section view along the line 2—2 of FIG. 1.

I claim:

The ornamental design for a stanchion for a car-top boat rack, as shown and described.
